UNITED STATES PATENT OFFICE.

HENRY F. CLARK, OF BELLE VERNON, PENNSYLVANIA, ASSIGNOR TO WINDOW GLASS MACHINE COMPANY, OF PITTSBURGH, PENNSYLVANIA, A CORPORATION OF NEW JERSEY.

SHEET-GLASS APPARATUS.

Application filed September 11, 1926. Serial No. 134,798.

This invention relates to sheet glass apparatus, and particularly to an improved form of drawing mechanism for raising a sheet of glass as it is drawn from a bath.

5 In the Foucault process of drawing sheet glass, the glass is drawn upwardly from a slotted clay block which is partly submerged in a bath of glass. It continues in its upward travel for a distance of some thirty 10 feet at which time it is cooled sufficiently to permit of its being cut into sheets.

Various lifting devices have been proposed, but the mechanism generally employed consists of a number of pairs of traction 15 rolls.

As heretofore constructed, each pair of rolls has been comprised of one fixed roll and one yieldable roll. The yieldable roll has generally been carried on bell cranks 20 having a weighted arm which urges the yieldable roll towards the fixed roll, thus providing sufficient pressure on a rising sheet of glass between the rolls to insure its upward travel.

25 The apparatus just described has been used for many years and while in some respects it is satisfactory, it falls far short of the ideal lifting mechanism because it does not take care of a very common situation 30 which arises in sheet glass drawing.

No matter how carefully the melting step is carried on, stones of various sizes will be found in molten glass. These stones move toward the point of draw and are picked up in the rising sheet. If the stone happens to project from the plane of the sheet on that side where the movable roll is provided, no harm results, for the roll simply moves outwardly until the stone has passed. It 35 will be understood that a large number of pairs of rolls are provided and that as a stone moves upwardly, each pair of rolls is temporarily ineffective for a short period, while the other rolls continue to draw the 40 glass upwardly.

45 Assume, however, that the stone projects from the other side of the glass sheet. The rolls on this side cannot yield and the glass sheet is therefore deflected away from the fixed roll a distance depending upon the amount the stone projects outwardly from the normal plane of the sheet surface. The sheet is, of course, engaged by rolls above

and below the fixed roll encountered by the stone and the yieldable rolls in these pairs 55 resist the sidewise displacement of the sheet. In consequence, it is subjected to a severe bending action and breakage frequently results.

I provide a drawing apparatus comprising 60 pairs of traction rolls, each roll in a pair being movable away from the sheet. I preferably employ counterweights for urging the rolls in a pair towards one another and in addition to these weights, I also employ 65 means for urging the rolls toward a normal central position in the plane of the rising sheet. Unless some such means is provided, there is the danger that the rolls may tend to occupy a position considerably to one side 70 of the plane of the sheet.

In the accompanying drawing which illustrates more or less diagrammatically a preferred form of the invention and certain modifications thereof, 75

Figure 1 is a side elevation partly broken away of a drawing tower embodying the invention;

Figure 2 is a side elevation of a portion of a tower showing a modified form of the 80 invention;

Figure 3 is a section taken on the line III—III of Figure 2;

Figure 4 is a view corresponding to Figure 2, but showing a still further modification; and 85

Figure 5 is a view illustrating a modified form of counter weight arm whereby the spring means may be eliminated.

Referring first to Figure 1, there is shown 90 a drawing tower indicated generally by the reference character 2 and provided with heat baffles 3 of usual construction. A sheet of glass G is shown as rising in the tower and engaged by traction rolls 4 arranged 95 in pairs.

The rolls are driven from a vertically extending power shaft 5 connected through mitre gears 6 to horizontal stub shafts 7. Each stub shaft 7 is connected through a spring coupling to a worm shaft 9 having right and left hand worms 10 thereon. The worms 10 engage worm wheels 11 which are carried to the shafts of the draft or traction rollers.

The draft rollers are mounted on the ver-

5 tically extending arms 12 of bell cranks pivoted on the wall of the draft tower at 13. The bell cranks each have a substantially horizontal arm 14 provided with an adjustable counter weight 15 for urging the draft rollers in each pair towards one another. It will be noted that the rollers lie between their points of pivotal movement 13 and the worms 10, thus insuring that the force applied through the gearing will urge the rollers towards the glass instead of away from it.

10 With the apparatus just described, it makes no difference whether a stone projects from either side of the rising sheet G, or from both sides thereof. The rollers are free to yield independently of one another. If a roller is forced away from the sheet, its worm wheel 11 simply rolls along the 15 worm 10 and the drive is uninterrupted, so that when the roll returns to its normal position, it immediately takes up its load.

15 Obviously each pair of rolls, as so far described, must be maintained in a state of nice balance if all the pairs of rolls are to occupy such a position that the sheet will not be deflected as it passes between them. It is desirable to provide means which will prevent pairs of rolls from being displaced 20 sidewise from the plane of the rising sheet. For this purpose, I employ casings 16 on the sides of the housing, each casing having a plunger 17 therein behind which is a compression spring 18. The plungers 17 bear 25 against the arms 14 and the springs 18 are placed under an initial compression. Obviously, if the rolls in a pair tend to move away from the central position, a spring on one side of a pair of rolls will be compressed 30 while the spring on the other side will be decompressed to a certain extent, thus setting up an unbalanced force which will tend to bring the rolls back to central position.

35 In Figure 5 there is illustrated a modified structure for accomplishing the same result. In this form of the invention, the arms 14^a, instead of being horizontal, are inclined downwardly at a rather steep angle. The weights 15^a have an effective arm r , and 40 with the arms inclined as shown in Figure 5, this effective distance varies rapidly upon even a slight movement of the rollers. They will, therefore tend to maintain a position wherein the effective moments set up by the 45 weights 15^a are in balance.

Figures 2 and 3 show a modified structure wherein the rollers in a pair are connected by spur gears 19. Instead of the rollers being journaled in bell crank arms, they are mounted in bearing blocks 20 movable on guides 21 secured to the side of the housing. Weighted bell crank arms 22 are provided, and these bear against the backs of the bearing blocks 20. A pinion 23 is mounted on a

55 stub shaft 24 and is connected to one of a pair of mitre gears 25. The other mitre gear is keyed to a vertically extending drive shaft 26 from which each pair of rolls is driven.

It will be noted that the guides 21 are inclined. As is well known, a pair of spur gears having their teeth cut according to the involute system will maintain their speed ratio regardless of the center-to-center distance. During the actual period of movement of the gears towards or away from one another, there will be a supplemental angular movement of the driven gear relative to the driving gear, due to the fact that the teeth vary in width. This condition obtains if the gears are moved towards or away from 80 one another along their common center line. I have shown the guides 21 as being placed at an angle to the common center line of the gears which corresponds to the angle made by the common normal of the gear teeth 85 with such common center line. This minimizes or eliminates the supplemental angular movement of the rolls and, therefore, eliminates a factor which might cause irregular traction and therefore breakage of the sheet.

In Figure 4 there is shown a still further modification wherein the rollers are mounted on the arms 27 of bell cranks pivoted at 28. The bell cranks have weighted arms 29 and are provided with the spring centering means described in connection with Figure 1.

A drive pinion 30 is mounted on a stub shaft 31 and meshes with a gear 32 on one of the pivot shafts 28. The gear 32 meshes 100 with a companion gear 33 and the gears 32 and 33 each mesh with pinions 34 on the roll shafts.

I have illustrated and described a preferred embodiment of the invention, but it will be understood that it is not to be limited, since it may be otherwise embodied within the scope of the following claims.

I claim:—

1. Sheet glass apparatus, comprising a 110 traction roll movable toward and away from a glass sheet, and means for supplying an increasing resistance to movement of the roll as it moves toward the glass sheet.

2. Sheet glass apparatus, comprising a 115 pair of traction rolls adapted to engage a glass sheet between them, each roll in the pair being movable away from the sheet, and means supplying an increasing resistance to movement of each roll as it moves toward the glass sheet.

3. Sheet glass apparatus, comprising a 120 traction roll adapted to engage a glass sheet, means urging the roll toward the sheet, and a yieldable stop for the roll.

4. Sheet glass apparatus, comprising a 125 pair of traction rolls, each roll in the pair being movable toward or away from the sheet,

and yieldable means associated with each roll for causing them to normally occupy a position immediately alongside the normal plane of travel of the glass sheet.

5 5. Sheet glass apparatus, comprising a pair of traction rolls, each roll in the pair being movable toward or away from the sheet, and yieldable means associated with each roll for causing them to normally occupy a position immediately alongside the normal plane of travel of the glass sheet, said yieldable means supplying an increasing

resistance to the other roll as they simultaneously move away from such position. 15

6. Sheet glass apparatus, comprising a pair of intergeared traction rolls, each roll in the pair being movable toward and away from the sheet, and means for guiding the rolls in such movement, said means being effective for minimizing supplemental relative angular movement of the rolls during their movement.

In testimony whereof I have hereunto set my hand.

HENRY F. CLARK.
